UNITED STATES PATENT OFFICE

2,146,665

TOY VEHICLE

Clarence G. Wood, Girard, Pa.

Application May 27, 1937, Serial No. 145,106

8 Claims. (Cl. 46—203)

This invention relates to toy vehicles. It is particularly designed to have certain peculiarities of operation which make it more attractive as a toy. It is designed to automatically and manually stop and start, preferably opens a door, lights a tail light, rings a bell during the stopping period, closes the door, stops the bell and shuts off the tail light upon the starting of the vehicle. Other features of the invention will appear from the specification and claims.

A preferred embodiment of the invention is illustrated in the accompanying drawings as follows:—

Fig. 1 shows a side elevation of a toy bus. Fig. 2 a bottom view of the bus.

Fig. 3 a detached view of the driving gear mechanism.

20 Fig. 5 a detached view of the control and bell.

Fig. 6 a detached view of the control mechanism.

Fig. 7 a view of the tail light and its mounting.
Fig. 8 a view of the battery mounting.

Fig. 9 a side elevation of a modification.
Fig. 10 a section on the line 10—10 in Fig. 11.
Fig. 11 a bottom view of the structure shown

Fig. 11 a bottom view of the structure shown in Fig. 9.

Fig. 13 is a detailed view of the gearing on the line 12—12 in Fig. 11.

Fig. 13 is a detailed view of the gearing on the line 13—13 in Fig. 14.

1 marks a body, 2 a door leading to the body, 3 front wheels, 4 the front axle, 5 a pivoted

40 front wheels, 1, the front axle, 2, a plate carrying the front axle, this plate being swiveled on a cross plate 6 carried by the frame, the swivel having sufficient friction to hold the position of the steering wheels.

Rear wheels 7 are carried by an axle 8. These rear wheels are driven by a spring mechanism as follows: The motor frame has the sides 9

45 These are spaced by a plate 10 at the front and secured to the walls of the bus by a cross-piece

11. The rear of the sides 9 are spaced by a cross-piece 12 which has a rearwardly extending strip 13 secured to the rear wall of the bus. A

50 strip 13 secured to the rear wall of the bus. A winding shaft 14 is journaled in the side plates (Figs. 3 and 4). A spring 15 has one end se-

cured to this winding shaft and the opposite end to a gear 16. The gear 16 meshes with a pinion 18. The gear 18 is fixed on a shaft 19, the shaft

55 The gear 19 is fixed on a shaft 18, the shaft being journaled in the side plates. A gear 20 is fixed on the shaft 19 and meshes with a pin-

ion 21 on the shaft 22, this shaft being journaled in the side pieces. A gear 23 is fixed on the shaft 22 and meshes with a gear 24. The pinion 24 is fixed on a shaft 25 journaled on the side

plates. The pinion 24 meshes a gear 26. The gear 26 is fixed on the axle 8 and this axle is driven through this train of gears. A gear 27 is fixed on the shaft 25 and meshes with a pinion 27a which is fixed on a shaft 28 journaled in the side plates of the frame (Figs. 5 and 6). A control mechanism is mounted on the shaft 28 comprising a centrifugally actuated friction shoe 29 which has a headed shank 30 extending through the shaft 28 and a centrifugal spring 31 around the shank. The shoe 29 operates in a shell 32 and as the centrifugal force overcomes the spring the shoe 29 rubs the shell and thus controls the speed and prevents the device running away.

A ratchet plate 33 is secured on the shaft 14 and has ratchet teeth 34 struck up in the plate and therefore slightly yielding, which engage detent 35 on the side plate so that as the spring is wound up it is locked by this ratchet means. 20

A stop pawl 36 is pivoted on a pin 37 arranged in the side plates of the frame and this pawl engages the gear 21a to stop the movement of the gears under the influence of the motor. The pawl has a lever arm 38 which is secured to a stop lever 39. The stop lever has a slot 40 through which the screw 41 extends, the screw 41 being secured to the side plate. The stop lever has a downward extension which projects below the bottom of the body and has a finger-hold 42 which permits it to be shoved forward or back for starting and stopping the motor.

The axle 8 is mounted in a sub-frame 43 which has two sides connected by cross plate 44 at the front. The two sides are pivoted on pins 46 at 35 the rear of the frame. A cam lever 47 is pivoted at 48 on the side frame, and a roller 49 mounted on the side of the gear 16 is adapted to engage in its orbit the cam lever 47 and push the lower end of that lever forward. The lower end of the lever has a cam surface 50 which engages the cross plate 44 and thus depresses the sub-frame 43 carrying the axle downwardly and the gear 26 out of mesh with the gear 24, thus stopping the driving of the axle. 45

It will be noted that this stopping will be momentary unless the lever 39 is operated because as the roller 49 passes the cam lever, the engagement of gear 26 with the gear 24 is re-established and the movement forward continued. An arm 51 is fixed on the shaft 25 and carries a bell tappet 52. A bell 53 is carried by bracket 54 secured by rivet 55 to the upper end of the cam arm 47. When the cam arm is operated by the roller, the upper end of this arm is moved rearwardly and the bracket 54 is moved downwardly carrying the bell 53 in an orbit of the tappet 52 so that the bell is sounded during the time the bus is stopped. A tail light 56 is arranged in the rear of the body. The light is connected at one end of the body to the main circuit and at the other end to the switch 39. The switch 39 is connected in series with the motor 22.

side by wire 57 with a switch plate 58 carried by the subframe. A switch member 59 is adapted to be contacted by the plate 58 when the subframe is depressed. The plate 59 is connected by a wire 60 with a terminal 61 secured to the body. The terminal is adapted to make contact with a battery 62. The battery 62 is carried by clips 63 secured to the body, and spring clip 64 maintaining the contact with the terminal. The other side of the light is grounded on the frame and connects through the battery. It will be seen during the period that the bus is stopped the tail light is lighted.

A rod 65 is secured to the upper end of the cam lever 47 and extends forwardly to the arm 66 extending inwardly from the door so that as the cam lever 47 is operated the door is opened and remains open during the period that the bus is stopped. A spring 67 pulls the rod 65 forward thus closing the door and also yieldingly carrying the upper end of the lever 47 forward and consequently the lower end to the rear position so as to be operated by the roller 49.

It will be noted that in this bus the motor is adapted to drive the bus and automatically stop and start it, that it may be manually stopped and started at will, that during the stopping period the door is opened, the bell rings and tail light lighted, and that upon the starting of the bus the door is closed, the bell ceases to ring and the tail light is dark.

In the modification the body, front axle and door are similar to that of the preceding structure and the rear wheels correspond. A frame 68 is provided with sides. These are connected at the front by cross piece 69 secured to a cross plate 70 extending from side to side of the body. The rear end of the frame has the inturned parts 70a which are secured to the rear of the body. The rear axle 71 carries the wheels 7 and this is journaled in the side of the frame 68. The rear axle is driven through the following mechanism. A spring 72 has one end secured to the frame and one end to a winding shaft 73. The winding shaft has a gear 74 fixed upon it. This gear has ratchet teeth 75 which are adapted to engage a pawl plate 76 splined on the shaft 73 (see Fig. 13). A spring 78 is arranged between a collar 79 on the shaft and the plate 76 and yieldingly holds the plate in engagement with the gear 74. This permits the winding of the spring through the ratchet mechanism. The gear 74 meshes a gear 80 which is carried by shaft 81, the shaft 81 being journaled in the frame. A gear 82 is fixed on the shaft 81 and meshes a gear 83. The gear 83 is fixed on the axle 71 so that as the bus is released this driving mechanism drives the bus through this gear train.

A cam 89 is fixed on the shaft 73 and in its rotation a cam 90 on the stop lever 91. The stop lever is pivoted on a pin 92 arranged in the frame. It has a downwardly extending off-set arm 94 with a shoe 95. The spring 93 holds the upper part of the lever in its forward position and throws the shoe off the floor. As the cam 89 rotates it contacts the cam plate 90, rotates the lever 91 and brings the shoe into contact with the floor and locks the bus. A cross-head 96 is fixed on the axle 7 and has the tappets 97. A bell 98 is carried by an arm 99 on the lever 91. When this lever is forced rearwardly by the cam 89 the bell is moved into the orbit of the tappet and the bell rings, so that as the bus is stopped the bell is rung. A rod 100 runs from the upper

part of the lever 91 to the door so that as the lever 91 is operated and the bus stopped, the door is swung open, and as the lever is swung forward releasing the bus the door is closed.

A battery 101 is mounted in the frame. It is connected by line 101a to a switch terminal 102. The switch plate 103 is carried by the lever 91 and as the lever swings to its stopped position the switch is closed. A line 104 extends from the plate 103 to the tail light 105 which is grounded to the frame so that as the cam is stopped the tail light is connected.

From this mechanism it will be seen that as the cam is started it moves intermittently, stopping and starting, with the sides of the cam 89. During the stopping the door is opened, the bell rung and the tail light turned on.

What I claim as new is:

1. In a toy vehicle the combination of a body; drive wheels for the body; a movable frame in which the drive wheels are mounted; driving means for the drive wheels; a stop means automatically stopping the drive, said means comprising devices moving the frame to disconnect the driving means from the drive wheels. 25

2. In a toy vehicle the combination of a body; drive wheels for the body; driving means for the wheels; a tail light for the vehicle; and means for automatically stopping and starting the drive, illuminating the tail light and cutting 30 off the illumination at predetermined intervals.

3. In a toy vehicle the combination of a body; drive wheels for the body; a door for the body; a tail light; driving means for the wheels; and means automatically stopping the drive, opening 35 the door, and illuminating the tail light after a predetermined interval.

4. In a toy vehicle the combination of a body; drive wheels for the body; a door for the body; a bell; driving means for the wheels; means automatically stopping the drive, opening the door and ringing the bell after a predetermined interval. 40

5. In a toy vehicle the combination of a body; drive wheels for the body; a door for the body; 45 a tail light; a bell; drive means for the drive wheels; and means automatically stopping the drive, opening the door, illuminating the tail light and ringing the bell after a predetermined interval.

6. In a toy vehicle the combination of a body; drive wheels for the body; an electric tail light for the body; means for supply current to the tail light; means for driving the wheels comprising a motor; a lever; and means actuated 55 by the lever stopping the drive and connecting the tail light after a predetermined interval.

7. In a toy vehicle the combination of a body; drive wheels for the body; a door for the body; an electric tail light; a source of current for the 60 tail light; means for driving the wheels comprising a motor; a lever actuated by the rotative part of the motor; and means actuated by the lever to stop the drive, open the door, and direct the current to the tail light after a predetermined interval. 65

8. In a toy vehicle the combination of a body; drive wheels for the body; driving means for the wheels; stopping and starting means automatically stopping and starting the drive at predetermined intervals; and manually actuated means for stopping and releasing the drive. 70

CLARENCE G. WOOD.
